UNITED STATES PATENT OFFICE.

HENRY M. QUACKENBUSH, OF HERKIMER, NEW YORK.

IMPROVEMENT IN SPRING AIR-PISTOLS.

Specification forming part of Letters Patent No. 178,327, dated June 6, 1876; application filed March 4, 1876.

To all whom it may concern:

Be it known that I, HENRY M. QUACKENBUSH, of Herkimer, Herkimer county, New York, have invented certain Improvements in Air-Pistols, of which the following is a specification:

These improvements relate to a class of air-pistols in which a spring-impelled plunger, traversing a cylinder whose outlet is the barrel, expels from such cylinder the air in advance of the plunger, and so that the air, rapidly driven forward through the barrel, intercepts, and expels from the latter the projectile, which has been previously inserted.

My present improvements relate, first, to means for enabling the plunger to be retracted and cocked, and the spring contracted, with much less labor and annoyance than have heretofore been necessary; and to this end I mount the barrel loosely in the bore of a tubular extension of the front of the air-magazine, and extend the rear end of the barrel rearward into such magazine, and against the forward end of the plunger, in order that, by pushing the barrel rearward into the magazine, the stress of the spring is overcome, and the plunger is cocked or set.

My improvements relate, secondly, to means for enabling the projectile to be readily inserted in the breech end of the barrel, to effect which I create in or near the rear end of the barrel an orifice, through which the projectile may be introduced into the bore of the latter, such orifice, when the barrel is in firing position, being closed, and concealed by the tubular extension before named, while a cross-channel or opening in such extension exposes the orifice, and affords an opportunity to insert the projectile.

My improvements relate, thirdly, to a compound trigger, of peculiar construction, whereby the power of its hold upon the plunger is varied, and, consequently, the degree of pull upon the trigger is diminished or increased.

The drawings accompanying this specification represent, in Figure 1, a longitudinal section; in Fig. 2, a plan of breech-loading mechanism, and in Fig 3 a cross-section of an air-pistol embodying my improvements.

In such drawings, A represents the body of the pistol, composed of a straight cylinder,

B, of uniform bore, which constitutes the air magazine or reservoir, and a suitable handle, C, the rear end of the air-magazine being open to admit entrance of air as the plunger is driven forward, and thus avoid tendency to a vacuum in rear of the latter.

The plunger is shown at D as playing to and fro of the forward part of the air-magazine, and fitting closely therein, while in rear of such plunger is disposed a coiled ribbon-spring, E, whose stress is exerted between the plunger and the rear end or cap of the magazine.

The trigger of this pistol, as before stated, is a compound one, and is composed of a latch, a, pivoted at its front end to the under side of the cylinder B, and playing within a slot, b, in the latter, while the other portion of the trigger is the ordinary finger-lever c, and is pivoted at its upper part within the slot or recess b, in rear of the latch a, and engaging the latter in such manner that when pulled it shall depress the free end of the said latch and release the plunger.

The method herein shown of swiveling the trigger-lever c to the latch a consists in the employment of a screw, d, which is screwed into the free end of the latch a, and so that its head e intercepts the nose f of the trigger-lever, while its inner end abuts against the bottom of the recess b. By advancing or retracting the screw d, the distance to which the latch a protrudes into the chamber B, and consequently the degree of its hold upon the plunger, is varied.

The forward end of the cylinder B is prolonged into a tubular extension, F, whose bore a' is coincident with that of the barrel, but of much less diameter, and in such extension F I cut a cross passage or opening, g, of a size sufficient to admit of the passage of a dart or other projectile.

The barrel of the pistol is shown at G as disposed within the bore of the extension F, and formed at its rear end with a tapering tubular head or valve, h, which fills a correspondingly-shaped seat, i, in which the extreme rear end of the bore a' terminates.

H, in the accompanying drawings, represents an opening or orifice, created in the barrel G, of a length sufficient to admit of the in-

roduction of a dart or other projectile into the bore of the barrel, the position of this opening H, with respect to the tubular extension F, being such that, when the barrel is in a firing position, as shown in Fig. 1 of the drawings, such opening is covered by the outer end or head h of such extension, and escape of air thereby prevented.

In using this pistol the most convenient method of cocking or setting the plunger, and the one attended with the least expenditure of strength, is to seize the handle in the right hand, and, placing the muzzle of the barrel upon the floor, push the barrel and plunger inward until the latter has passed in rear of, and is intercepted and held by, the trigger-latch a. The barrel is now partially returned to its original position, or until its orifice H coincides with the passage g, before named, when the projectile is inserted within the bore of the barrel, and the latter pulled outward to its extreme limit, the orifice H being in the act closed by the head h, and the tapering annular head or valve h fitting tightly within the seat i. The pistol is now loaded and cocked. A pull upon the trigger-lever c releases the plunger, and the latter is driven suddenly forward by the stress of the spring E until it reaches the front end of the chamber B, in its passage forcing the air from such

chamber forward through the barrel, and expelling the projectile from the latter.

I claim—

1. The combination of the barrel, spring-impelled plunger, and air-magazine, under such an arrangement that the barrel is susceptible of being pushed into the latter, and cocking or setting the plunger, substantially as and for the purposes stated.

2. The sliding barrel, formed with an orifice in its side, as described, in combination with the tubular barrel-support F, provided with a passage or opening, g, substantially as set forth.

3. The tapering annular head or valve h, upon the rear end of the barrel, in combination with the orifice or valve-seat i, substantially as herein shown, whereby escape and loss of air during the advance of the plunger is avoided, essentially as and for the purposes stated.

4. The compound trigger, herein shown and explained, consisting of the latch a, screw d, or its equivalent, and trigger-lever c, substantially as and for the purposes stated.

HENRY M. QUACKENBUSH.
